LOUD SPEAKER

Bernard A. Engholm, Lakewood, Ohio, assignor
to The Rola Company, Cleveland, Ohio, a cor-
poration of Ohio

Application July 30, 1932, Serial No. 626,795

3 Claims. (Cl. 179—146)

This invention relates to radio loud speakers and particularly to those, which are intended for use in motor vehicle installation. One form of loud speaker mounting, which has been found to be satisfactory for this purpose comprises a single-bolt, which is carried by the field coil and which extends rearwardly from the field coil shell and supports the speaker on the dash board. In such cases, the speaker housing embodies a hollow member which is fastened to the diaphragm housing at the forward portion thereof, and adjacent the clamping ring, which holds the rim of the diaphragm in place. It is desirable therefore, to close the back of the speaker housing and at the same time to support it so as to maintain it in operative condition notwithstanding the fact that it may be subjected to excessive vibration during use. The practice heretofore has been to extend the speaker housing back to the end of the field coil shell and to close the back with a float cardboard disc which has an opening through which the mounting bolt extends. To allow free movement of air however, in back of the diaphragm, it has been necessary to provide openings in the disc and then to utilize a wooden spacer between the disc and the dash board to permit the free circulation of air behind the speaker. Furthermore, to obtain sufficient rigidity, it has been necessary to attach the outer edge of the disc to the casing.

An object of my invention is to provide a construction, which will achieve the desired closing of the back of the speaker housing in a satisfactory and efficient manner and which is well adapted for use in connection with the single bolt mounting of loud speakers.

Referring now to the drawing, the figure shows a vertical section through a loud speaker embodying my invention.

I have shown my invention in connection with an electrodynamic speaker having a field coil 10, a shell 11 therefor, a diaphragm 12, a diaphragm housing or support 13, and an outer housing 14. The outer housing is shown as a hollow member, which has an inturned flange 15 at the forward edge thereof which is fastened to an outwardly extending flange 16 on the housing 13. The rim of the diaphragm is then preferably fastened between these two flanges. Where metal is used for making the outer housing, I prefer to insert a sleeve of sound absorbing material, such as cardboard 17 and to terminate at the rearward end of the sleeve short of the rearward edge of the housing 14. This provides a shoulder 18 for receiving the rim of the closure 25.

In the preferred arrangement, the rearward edge 19 of the outer housing terminates in a plane, which is offset from a plane which passes through the rearward end of the field coil shell. A single bolt 21 which is shown as being rigidly fastened to the field coil core projects rearwardly from the shell and extends through the dash board 22 and operates to hold the speaker in operative position thereon.

To close the back of the speaker housing, I provide a closure 25 which is shown as having a frustro-conical body portion, and as having a radially extending portion 27 adjacent the apex end thereof. The base 26 of the closure fits snugly against the shoulder 18 while the portion 27 is provided with an opening through which the bolt 21 is passed. Thus when the nut 28 is drawn up tightly, the closure is rigidly held against the dash board and the speaker housing is rigidly held in turn by contact with the closure.

An advantage of my invention is the fact that the back of the speaker may be closed without the necessity for using a spacing block and without the necessity for fastening the closure to the speaker housing. Thus the speaker can be quickly dismantled for service work and when in use can be handled rigidly in position against the dashboard by a single bolt.

I therefore claim:—

1. In combination, a support having an opening therein, a loud speaker having a field coil shell disposed on one side of the support and in close proximity thereto, a diaphragm associated with the shell, a housing enclosing the speaker and extending backwardly toward the support and terminating short thereof, the housing having substantially uniform cross-sectional area throughout its length, a frustro-conical closure for the back of the housing, the base of said closure being in close fitting engagement with the wall of the housing and having an opening adjacent the apex portion thereof, a single bolt projecting rearwardly from the shell and extending through the opening in the support and threaded means on the bolt for locking the shell and closure to the support.

2. In combination, a support, a loud speaker comprising a field coil shell, a diaphragm, an inner housing associated therewith, the inner housing being mounted upon the shell and extending away from the support, an outer housing having an inturned flange and having substantially uniform cross-sectional area throughout its length, means extending through the

flange for locking the outer housing and dia-
phragm to the inner housing, whereby the outer
housing is supported only at the diaphragm end
thereof, a closure for the back of the outer hous-
ing, said closure comprising a frusto-conical
5 member having a close fitting engagement with
the outer wall of the housing, and the apex
end of said closure being disposed between the
shell and the support, and a bolt carried by
10 the shell and extending through the support,
said bolt operating to lock the speaker to the
support and to hold the closure in locked posi-
tion with reference to the shell.

3. In combination, a loud speaker having a
field coil shell, a housing, a closure for the back
of the housing, said closure having the midpor-
tion thereof in abutting engagement with the
back of the shell, and having the outer marginal 80
portions thereof in engagement with the rear-
ward end of the housing and having a surface
extending from the shell to the housing,
said surface being inclined with reference to
the housing, there being ventilating apertures in
85 the inclined surface, and single means for lock-
ing the shell to a support.
